UNITED STATES PATENT OFFICE.

GEORGE MELVIN LONG, OF BOSTON, MASSACHUSETTS, ASSIGNOR TO H. L. JUDD COMPANY, INC., OF WALLINGFORD, CONNECTICUT, A CORPORATION OF DELAWARE.

DESIGN FOR A DRAPERY-POLE CENTER.

Application filed May 2, 1928. Serial No. 26,531. Term of patent 3½ years.

To all whom it may concern:

Be it known that I, GEORGE MELVIN LONG, a citizen of the United States, residing at Boston, in the county of Suffolk and State of Massachusetts, have invented a new, original, and ornamental Design for a Drapery-Pole Center, of which the following is a specification, reference being had to the accompanying drawing, forming part thereof.

Fig. 1 is a front elevation of a drapery pole center, showing my new design.

Fig. 2 is a cross sectional view of the same, substantially on the plane of the line 2—2 of Fig. 1.

I claim:

The ornamental design for a drapery pole center, as shown.

GEORGE MELVIN LONG.
